CLAIM

The ornamental design for a wallet for displaying, storing and transporting military insignia, as shown and described.

DESCRIPTION

FIG. 1 is a perspective view of my new wallet shown opened.

FIG. 2 is a top perspective view of the wallet shown folded once and closed, and illustrating a creased region bisecting the wallet where it may be folded again, for example, for placement in a pocket. A view of a bottom side is a mirror image thereof.

FIG. 3 is a top planar view of the wallet in an open position showing positioning of hook-and-loop fastening strips.

FIG. 4 is a top side elevation view of the wallet closed, the bottom side elevation view being a mirror image.

FIG. 5 is a cross-sectional view along line 5—5 of FIG. 3, showing an insignia backed with cooperating hook and loop fastener and held in place on a hook and loop fastener strip; and,

FIG. 6 is a cross-sectional view along line 6—6 of FIG. 3, showing an insignia pinned through a hook and loop fastening strip.

The dashed lines showing various military insignia are directed to environment and form no part of the claimed design.
